UNITED STATES PATENT OFFICE.

THEODOR DEPPE, OF LEIPZIG, GERMANY.

SAFETY APPARATUS FOR SUPPORTING LADDERS.

Application filed April 20, 1927, Serial No. 185,278, and in Germany May 12, 1926.

This invention relates to an improved safety apparatus for supporting ladders and preventing the same slipping on the ground, while means are provided thereon for placing the ladder in any inclined position.

The accompanying drawing illustrates the improved safety apparatus: Figs. 1, 2 and 3 are respectively a plan view, a right-hand side view, and a left-hand side view, of the same in its vertical position, while Fig. 4 is a similar view to Fig. 2 of the apparatus with the main part of the same in inclined position with the lower end of a ladder post therein; Figs. 5 and 6 are respectively a plan view and a side view of a detail belonging to the apparatus.

A rectangular base plate *a*, of which the edges may be recessed at certain places for a reduction of its weight, is on its underside provided with anti-slipping members *b*, preferably of rubber or the like.

Said base plate carries near its front edge *V* a transverse abutment-wall *c* against which the ladder post *P* (Fig. 4) is placed with its lower corner bearing upon transverse ribs *d* provided on the upper surface of the base plate behind said transverse abutment-wall *c*.

At the left-hand edge of the base plate *a* fixed upright bracket *e* is arranged and provided with an elongated vertical slot *f*, in which a horizontal headed bolt *g* is guided by means of its square part *x*, said bolt carrying at its outer end a fixed round disc *h* and at its inner end a rectangular disc *i* and one lateral wall of a rectangular caselike frame *k*, all being centrally mounted thereon. Said frame *k* embraces the lower end of the ladder post *P* (Fig. 4) and is so turnable on the bolt *g* that the ladder post, and thus the whole ladder, can be adjusted to different inclined positions. Said turning movement of the frame *k* is limited by two lateral fixed head-pins *m* thereon engaging in curved slots *l* provided in the disc *i* and having the centre of their radii located in the axis of the bolt *g*. Instead of two such slots, of course, one only would be sufficient for the purpose in question.

To ensure a correct position of the frame *k* for its being turned with the lower end of the ladder post *P* inserted therein in vertical position, the bolt *g* must then be located exactly in the middle of the elongated slot *f*. To this end, the rectangular disc *i* has a wedgelike lower extension *i'* and

bears therewith upon two blade springs *n* mounted on the front and rear ends of the lower part of the bracket *e*. Thereby, the frame *k* is allowed to yield somewhat for placing the ladder in inclined position.

The inner lateral face of the frame *k* adjacent to the disc *i* is toothed, while a movable clamping jaw *o* is suspended between the short side walls of the frame opposite to said lateral toothed face and provided with an upper knee-piece *p* having an outer depending member with an elongated slot *q* therein, through which the shaft of a pressure-screw *r* is freely passed so as to act from outside upon the middle of said jaw. By these means, the ladder post is firmly gripped within said frame *k* while the jaw *o* is allowed to tilt somewhat at its lower part in case that the ladder post has a tapered end.

For placing the ladder on very slippery ground, it is desirable to place below the base plate *a* another base plate *s* fitted with pegs *u* and to lock the base plate *a* thereon by means of locking bolts *t* (Figs. 5 and 6).

If desired, the apparatus can easily be so modified that the ladder can be placed in inclined positions not only in one direction but in both directions from its vertical position.

The operation of the apparatus is very simple:

The ladder is inserted with the lower end of its post in the frame *k* in vertical position (Figs. 1 to 3), the ladder post being then clamped fast in the frame by means of the screw *r* and the frame is yieldingly turned until the ladder and thus its post *P* (Fig. 4) assumes the desired inclined position, in which it bears against the abutment-wall *c* and upon the ribbed bottom *d* of the base plate *a*.

What I claim, is:

A safety apparatus for supporting ladders, comprising a base plate, anti-slipping members on the underside of the latter, an abutment-wall near the front edge of said base plate, a ribbed upper surface on said base plate behind said abutment-wall, a fixed upright bracket on one side of said base plate behind said abutment-wall having an elongated vertical slot therein, a horizontal headed bolt having a square part guided in said slot, a fixed round disc on the outer end of said bolt, a rectangular disc centrally mounted on the inner end of

said bolt, blade springs against which bears the lower end of said disc, a rectangular frame turnably mounted on the inner end of said bolt and having a slot-and-pin connection with said disc limiting its turning movement, a toothed lateral inner face on said frame, a movable clamping jaw in said frame opposite said toothed face adapted

to tilt somewhat at its lower end, and a pressure-screw acting upon said clamping jaw for clamping the lower end of a ladder post in said frame. 10

In testimony whereof I have hereunto set my hand.

THEODOR DEPPE.
